UNITED STATES PATENT OFFICE.

CLARENCE E. BEACH, OF BINGHAMTON, NEW YORK.

SIGNALING SYSTEM.

Application filed January 7, 1920. Serial No. 349,949.

To all whom it may concern:

Be it known that I, CLARENCE E. BEACH, a citizen of the United States, residing at Binghamton, county of Broome, and State 5 of New York, have invented certain new and useful Improvements in Signaling Systems, of which the following is a specification.

This invention relates to signaling systems comprising a central station having suitable current supply and manifesting mechanism, a plurality of distant signal initiating stations having circuit-breaking and circuit-grounding mechanism, and a normally closed line circuit in which such stations are connected.

This invention is especially adapted for use in connection with the signaling system disclosed in my copending application 20 Serial No. 335,430, filed November 3rd, 1919.

In my aforesaid application, means are disclosed responsive to current flow in each of the line conductors and in a ground connection at the central station for manifesting signals of the initiating stations; but no means is disclosed by said application for preventing the manifesting means for the central station ground connection from 30 responding to the strokes of both of any two initiating stations which may act concurrently; such concurrent response would not afford an intelligible manifestation of the code signal of either of such stations.

Such double-strokes are experienced when the contacts of one of such stations have acted to ground the circuit, and thereupon the contacts of another of such stations act to close the circuit and, before the contacts 40 of such second station act to add the ground connection to such closure, the contacts of such first named station break the circuit; thus formulating an unintended closure and break which may be of sufficient duration to cause the central office manifesting mechanism to respond thereto, with the result that there will be two responses of said mechanism in comparatively quick succession, when but one response was intended.

The principal object of this invention is to provide a signaling system comprising a circuit including a plurality of code signal ini-

tating stations, and having mechanism arranged to manifest the code signals of each 55 of any two concurrently acting stations or of any one short-circuited station, without manual readjustment and without manifesting any false code signal.

Other objects of this invention will be 60 in part obvious and in part specifically pointed out in the following specification.

In constructing this invention a plurality of signal initiating stations are connected by a circuit including manifesting 65 mechanism and a suitable current source, said manifesting mechanism being arranged for response to circuit breaks or closures (as the case may be) and to the grounding of said circuit at any initiating 70 station.

When operating conditions are such that it may be desirable to at all times assure the manifestation of the code signals of each of two initiating stations in the event 75 of the concurrent activity of a plurality of such stations; and such that it would be undesirable should manual adjustment be needed, in the event of a circuit break, in order to assure intended response to the 80 code signal of any actuated initiating station;—the manifesting mechanism should be independently responsive to breaks or closures (as the case may be) in either side of the circuit, as well as to the grounding 85 of said circuit at any initiating station.

In the use of certain types of initiating stations and circuits, the signaling impulses formulated under normal circuit conditions, incident to the grounding of the 90 circuit during the action of any initiating station, are likely to cause such response of manifesting mechanism intended for response to the grounding of the circuit as to indicate unintended code signals. In the 95 use of circuit arrangements and mechanism arranged to permit independent manifestation of the respective code signals of two concurrently acting initiating stations, as hereinbefore pointed out, it is undesirable that said mechanism shall act to manifest an intermingling of the code signaling impulses of any two such stations. When operating conditions render it desirable that such unintended and undesirable results 100 shall be avoided,—means are provided

whereby the action of such manifesting mechanism, in response to any break or closure of said circuit, renders said mechanism unresponsive to the grounding of said circuit at any initiating station.

In order to prevent the response of said mechanism to ground connections which may commence or terminate between one break or closure of a code signal and another,—said means should render said mechanism unresponsive to such ground connections for the time, following each response of said mechanism to a break or closure of said signaling circuit, which time is longer than the longest interval between the strokes of any code signal.

When said manifesting mechanism includes paper feeding means adapted to be conditioned upon each stroke of a signal to run for a time longer than the longest interval between strokes of any signal,—said feeding means may be employed in accordance with this invention for rendering said mechanism unresponsive to ground connections during the running of such feeding means in response to breaks or closures of the signaling circuit.

For the purpose of preventing the formulation of current impulses calculated to cause the manifestation of double-strokes during code signals, means are provided at each initiating station for grounding the signaling circuit at such station throughout every closure incidental to the transmission of the code signal of such station to which response of the central office manifesting mechanism should be made. Thus: if said manifesting mechanism is arranged to act in response to circuit closures but not to breaks of the circuit incident to code signals,—such ground connections should become effective at the commencement of the first closure following the first break incident to the transmission of any code signal, and should be effective throughout all succeeding closures of such signal except that, after being effective for a suitable period during the final closure of the circuit following the transmission of any code signal, said ground connection should be rendered ineffective for reasons well understood by those skilled in this art; and if said manifesting mechanism is arranged to act in response to circuit breaks but not to closures of the circuit incident to code signals, such ground connection should become effective a suitable period below the first break incident to the transmission of any code signal and should be effective throughout all succeeding closures of such signal, except that said connection should not be effective during any part of the final closure of the circuit following the transmission of any code signal.

For the purpose of facilitating the understanding of this invention, and for the

further purpose of setting forth in greater detail certain features thereof,—an embodiment thereof is illustrated in the accompanying drawings, where like reference characters denote similar parts throughout, and in which—

Figure 1 is an illustrative diagrammatic representation of a signaling system embodying this invention, and

Figure 2 is an enlarged view showing the arrangement of certain features of the registers E and G of Fig. 1.

Referring to Fig. 1: A represents an open-delta connected three-phase current source, two of the phases of said source being connected to respective ends of a signaling circuit and the other phase being connected to the ground. Said source therefore constitutes means for applying an electromotive force to said circuit and for applying a second electromotive force to said ground connection, which electromotive forces differ in phase from one another.

The alternating current relays B, C and D are located in the central station and are connected respectively in one side of said circuit, in said ground connection, and in the other side of said circuit; and the registers E, F and G are likewise located in the central station and are arranged for response to said respective relays, said relays and registers therefore serving as manifesting mechanism distinctively responsive to signaling impulses in either side of said circuit or in said ground connection.

The signal initiating stations L, M and N are serially connected in said signaling circuit, and each of said stations has code signal formulating means comprising a code-wheel 20, and has circuit-breaking and circuit-grounding mechanism comprising the code contacts 21, 22 and 23 operable thereby, the contacts 21 and 22 being connected through the conductors 24 and 25 to the circuit terminals 26 and 27 respectively, and the contact 23 forming part of a normally open ground connection, the remaining parts of which connection being the conductor 28, normally open contacts 29 and 30, the conductor 31, ground terminal 32, and ground connection 33.

A notched disc 34 is arranged to operate the contact 30 so that, when the code wheel has been set in motion, while or immediately after the first notch of the code-wheel 20 is presented to the trailing end of the contact 23, said disc will move contact 30 into engagement with contact 29, and will hold said contacts so engaged until after the code-wheel 20 has moved the contacts 21, 22 and 23 into engagement for the last time before coming to rest after any action thereof.

Suitable means is provided at each initiating station for causing desired action of the

code-wheel 20 and disc 34 thereat, which means may comprise any suitable well-known form of clockwork; with desired starting facilities, such as the handle 35.

5 The details of such means form no part of this invention; and as various forms of clockwork suitable for use at initiating stations, such as those shown, are well-known and their relative suitability will be readily apparent to those skilled in this art, representation of further details of such clockwork is therefore omitted in the interests of simplicity and clearness.

The code-wheels 20 are shown as being 15 of the so called "closed type" (i. e. arranged to close contacts throughout all pauses and to open them for substantially uniform and comparatively brief intervals for each stroke) although, as will be herein- 20 after more fully pointed out, so called "open type" wheels (i. e. arranged to open contacts throughout all pauses and to close them for substantially uniform and comparatively brief intervals for each stroke) 25 may be employed without departing from the spirit of this invention.

The relays B, C and D are shown as each controlling a normally open local circuit including a suitable current source, the winding 30 of the controlling magnet of a register, and parallel paths connecting visible and audible alarming mechanism.

For convenient representation, a separate current source is shown for each of said 35 local circuits, but it is obvious that such circuits might be supplied from a common source, as, for example, the source A.

As shown, the normally open local circuit controlled by the relay B includes the battery 36, the winding of the controlling magnet of register E, and parallel paths one 40 of which includes the lamp 37 and the other of which includes the winding of alarm relay 38; the alarm bell 39 being suitably controlled by the relay 38, subject to the disconnecting switch 40.

The controlling mechanism of register E is arranged to act in response to breaks of the local circuit in which the winding of 50 the controlling magnet of said register is connected, and said register is equipped with usual paper feeding train mechanism adapted to be conditioned by each stroke of a signal to run for a time longer than the longest 55 interval between strokes of any signal.

The normally closed contacts 41 and 42 are controlled by said train so as to be open during the running thereof.

Fig. 2 shows a typical arrangement of register mechanism for the actuation of paper marking and feeding devices, and illustrates the manner of utilizing such mechanism for controlling the contacts 41 and 42. The main wheel 71 is mounted upon a shaft 72. Said shaft is driven by the main spring 73

and is connected to the wheel 71 through the ratchet 74 and the dog 75, which dog is held in engagement with said ratchet by the spring 76. The pinion 77 is mounted upon the shaft 78, is driven by the wheel 71 and 70 drives the gear 79. The pinion 80 is fixed upon the shaft 81 and drives the cam 82 and the detent arm 83. Suitable paper marking mechanism (not shown) may be connected to the shaft 81 so that, incident 75 to each revolution of said shaft, the paper tape will be suitably marked.

The detent lever 84 is pivoted at 85 and comprises an arm 86; the end of which arm is bent at right angles thereto, and is so positioned as to be adapted for movement into and out of the path of the free end of the arm 83 incident to the swing of said lever 84 around its pivot 85. The lever 84 also comprises the arm 87 near the free end of which the pin 88 is mounted in such position that it may be alternately engaged by the ledges 89 and 90 carried by the escapement arm 91. The arm 91 is pivoted at 92 and moves with the arm 93. The armature 94 is secured to the arm 93 in such relation to the magnet 95 that, when said armature is in attracted position, the ledge 90 will be disposed in the path of the pin 88; and such that, when said armature is in retracted position, the ledge 89 will be disposed in the path of said pin.

A finger 96 is secured to the arm 87 and extends in the path of the pin 97 carried by the arm 83; so that, during the rotation of said arm, said pin will engage said finger and thereby move said lever from a position in which the end of the arm 86 is withdrawn from the path of the arm 83 (and the pin 88 is disposed below the ledges 89 and 90) 100 to a position in which the end of the arm 86 will be disposed in the path of the arm 83 and the pin 88 will be situated above the ledges 89 and 90. 105

The downward movement of the arms 87 and 93 is actuated by gravity, which may be supplemented, if desired, by the use of suitable springs (not shown).

The sector 100 is carried by an arm 101; which arm is pivoted at 102 and carries a roller 103 disposed in the path of the cam 82. A spring 104 is provided for urging the arm 101 toward the cam 82. One end of said spring is secured to the frame at 105 and the other end of said spring is secured 110 to the arm 101 at 106.

The pinion 107 is journaled upon the shaft 108 in the path of the sector 100, so that the movement of said sector will rotate said pinion.

The ratchet 109 is also journaled upon the shaft 108 and moves with the pinion 107. The wheel 110 is fixed upon the shaft 108 and carries the dog 111 and the spring 112 for holding said dog in engagement with 125

said ratchet 109. The cooperation between the ratchet 109 and the dog 111 is such that movement imparted to the pinion 107 by the pull of the spring 104 upon the arm 101 will cause rotation of the wheel 110 and shaft 108, and movement imparted to said pinion through the engagement of the roller 103 by the cam 82 need not rotate the wheel 110 therewith.

10 Suitable paper feeding mechanism (not shown in Fig. 2) is arranged for actuation by the shaft 108.

The pinion 113 and escapement wheel 114 are mounted upon the shaft 115, said pinion 15 being positioned for engagement thereof by the wheel 110, and said escapement wheel being positioned for engagement thereof by the pallet 120 which is mounted upon the shaft 116 and moves with the pendulum 117, 20 for the purpose of governing the speed of rotation of the shaft 108 and parts moving therewith.

An extension 118 is secured to the arm 101 and carries an insulating pin 119 in the 25 free end thereof, which pin is arranged to engage the contact 42 and holds same against the contact 41 while the arm 101 is in its normal elevated position.

The various parts shown in Fig. 2 are 30 normally positioned as shown; so that, upon the effective energization of the magnet 95, the armature 94 will be moved from retracted to attracted position, thereby withdrawing the ledge 89 from the path of 35 the pin 88, whereupon the arm 87 will move downwardly until said pin 88 is brought into engagement with the ledge 90. Such downward movement of the arm 87 will be insufficient to swing the end of the arm 86 40 out of the path of the arm 83.

When the magnet 95 is thereafter de-energized,—the armature 94 will move to retracted position (as shown) thereby with- 45 drawing the ledge 90 from the path of the pin 88, and thus permitting the arm 87 to swing downwardly so as to bring the end of the arm 86 out of the path of the arm 83.

When the arm 83 is disengaged by the 50 end of the arm 86, as just described, the shaft 81 will quickly rotate, thus causing the pin 97 to engage with the finger 96 and thereby restoring the lever 84 to its normal position, and causing the cam 82 to move the arm 101 downwardly and thereby store 55 energy in the spring 104. Such rotation of the shaft 81 will also serve to actuate such paper marking mechanism as may be associated therewith.

When the arm 101 is moved downwardly, 60 as just described, the extension 118 will carry the pin 119 away from the contact 42; and said contact will thereupon move away from the contact 41. During such downward movement of the arm 101,—the 65 sector 100 will rotate the pinion 107 and the

ratchet 109 in counter-clockwise direction, thus moving the teeth of the ratchet past the dog 111 without rotating the wheel 110.

At the conclusion of the rotation of the shaft 81, the rise of the cam 82 will be withdrawn from the path of the roller 103, and the spring 104 will thereupon act through the arm 101 and the sector 100 rotate the pinion 107, wheel 110 and shaft 108; subject to the retarding effect of the engagement 75 of the pallet 120 with the escapement wheel 114. Such retarding effect is so proportioned that, when the arm 101 has been moved downwardly, as just described, said arm will not there-after be sufficiently 80 elevated to act through the extension 118 and pin 119 to move the contact 42 into engagement with the contact 41 for a time longer than the longest interval between the impulses of any signal. 85

Should the magnet 95 be again energized and then deenergized, during the running of the paper feeding train as just described, the shaft 81 will again revolve and will thus act through the cam 82 to annul the 90 upward movement of the arm 101 which took place since the preceding revolution of said shaft.

From the foregoing it will be evident that 95 said paper feeding train is adapted to be conditioned, upon each circuit impulse of any signal responded to by the recording mechanism shaft 81, to run for a time longer than the longest interval between impulses of any signal; and that means, 100 comprising the extension 118, pin 119, and contacts 41 and 42, are arranged to render the register F unresponsive to the ground connection during the running of the paper feeding trains of either the register E or 105 the register G.

The normally open local circuit controlled by the relay D correspondingly includes the controlling magnet of register G and other instrumentalities responsive thereto, in a 110 manner corresponding to that just described in reference to the local circuit controlled by the relay B.

The local circuit controlled by the relay C includes the controlling magnet of the 115 manifesting device F (which device may be a register, as shown, or may be a bell, lamp or other device for visually or audibly manifesting signals, as, for the purposes of this invention, this device need not be provided with a paper feeding train) together with other instrumentalities responsive to said circuit, in a manner corresponding to that just described in reference to the local circuit controlled by the relay B; but said register F does not require circuit controlling contacts such as the contacts 41 and 42 supplied for registers E and G. The local circuit controlled by said relay C also serially includes the normally closed contacts 41 and 42 of registers 120 125 E and G. The local circuit controlled by said relay C also serially includes the normally closed contacts 41 and 42 of registers 130

E and G. It is therefore evident that means are provided, which are operable incidentally to the manifestation of each signaling impulse in said circuit, for rendering 5 said register F unresponsive to signaling impulses in said ground connection incidental to the actuation of the grounding mechanism of any initiating station.

If desired, the notched disc 34 of the 10 various initiating stations may be arranged to close the contacts 29 and 30 whenever the code-wheel 20 is set in motion and before the first notch of the said code-wheel is presented to the trailing end of contact 15 23, in which event said disc should be arranged to hold said contacts so engaged only until the contacts 21, 22 and 23 have moved out of engagement for the last time before coming to rest after any actuation 20 of the code-wheel, so that said contacts 29 and 30 will always be separated when the circuit closes for the last time at the conclusion of any signal. If the arrangement 25 of the disc 34 is revised as just indicated, the code-wheel 20 may be of either of the open type or the closed type, although open type code-wheels may cause incorrect signal manifestations if employed with notched discs arranged as hereinbefore first described. 30

If the notched discs are arranged in accordance with the revision just referred to, regardless of whether the code-wheels are of the open or closed type, the mechanism 35 of the registers E, F and G should be arranged to act reversely to the manner hereinbefore described; i. e. registers E and G should be arranged to act in response to closures and register F to breaks, of the 40 respective local circuits in which the windings of the controlling magnets of such registers are connected. In any event each initiating station should be arranged to ground every closure the effectiveness of 45 which is essential to correct manifestation of the code signal thereof by the type of manifesting mechanism employed in connection therewith, and such grounding should be effective throughout each of such 50 closures, except the closures which precede and follow such signals. In the instance of the normal closure preceding a signal, if response should be made to the breaking thereof, such closure should be grounded 55 for a suitable period immediately preceding the termination thereof. In the instance of the final closure following a signal, if response should be made to the commencement thereof, such closure should be grounded 60 from the commencement thereof for a suitable period thereafter.

Under certain conditions which do not render it expedient to provide for the independent manifestation of the code signals 65 of two concurrently acting initiating sta-

tions, the relay C and either the register E or the register G may be omitted, the local circuit of the register F being then arranged to be controlled by the relay whose previously associated register has been thus 70 omitted, the responsiveness of the register F being controlled by the remaining register E or G (as the case may be). If the foregoing rearrangements are made, the ground connection may be transferred 75 to the terminal of the current source nearest to the line relay which controls the register F.

The operation of the system shown in the accompanying drawing is as follows: Under 80 normal conditions a current path is provided from the left-hand terminal of the source A through conductor 43, winding of relay B and conductor 44 to terminal 26 of initiating station L thence through conductor 24, contacts 22, 23 and 21, and conductor 25 to terminal 27 of said station, thence through conductor 45 to terminal 26 of station M, thence correspondingly through station M to terminal 27 thereof, thence 85 through conductor 46 to terminal 26 of station N, thence correspondingly through said station to terminal 27 thereof, thence through conductor 47, winding of relay D and conductor 48 to the right-hand terminal 90 of source A; the secondary windings 49 and 50 of said source being serially connected between said conductors 48 and 43, and said windings being excited by the primary windings 51 and 52 respectively; said winding 51 being connected between the phase wires 54 and 55 and said winding 52 being connected between the phase wires 53 and 54 of a suitable three-phase alternating current supply circuit. Inasmuch as the contacts 29 and 30 of the ground connection of all of the initiating stations normally stand open; there will be no current flow from the junction between secondary windings 49 and 50 through conductor 56, windings of relay C and conductor 57 to the ground; the current flow through the signal circuit will cause the armatures of relays B and D to occupy their attracted positions, and a lack of current flow in the 105 ground connection will permit the armature of relay C to occupy its retracted position, the controlling magnets of registers E, F and G will be de-energized, the paper feeding trains of said registers will be at rest 110 and the contacts 41 and 42 associated with registers E and G will be closed.

Inasmuch as the respective local circuits are open,—the alarm lamps 37 will not be lighted, the alarm relays 38 will be de-energized, and the armatures of said relays will be in retracted position thus breaking the current path through their associated alarm bells 39, even when the disconnecting switches 40 are all closed. 130

If now one of the initiating stations is set in action, as by the operation of the starting handle 35 thereat, the code-wheel 20 of such station will be rotated one or more times (depending upon the arrangement of the mechanism at the station for response to the operation imparted to the starting handle 35) and, when the first notch of the said code-wheel is presented to the trailing end of the contact 23, said contact will drop away from the contacts 21 and 22 and thereby break the signaling circuit. During the continued rotation of the code-wheel 20, and before said code-wheel brings the contact 23 into engagement with the contacts 21 and 22, the disc 34 will move the contact 30 into engagement with the contact 29, thereby closing the ground connection of said station.

When the circuit is broken at the contacts 21, 22 and 23 of any station, as just described, the relays B and D are de-energized and their armatures moved to retracted position thereby closing the local circuits of registers E and G so as to cause the electro-magnets of said registers to be effectively energized, the associated alarm lamps 37 to be lighted, the associated alarm relays 38 to be energized, and the associated alarm bells 39 to sound. Such energization of the electro-magnets of these registers will not cause the actuation of the marking or paper feeding mechanism thereof, as these registers are arranged to act to mark the paper and start the paper feeding mechanism only in response to changes in the condition of their respective controlling magnets from abnormal to normal, as hereinbefore more fully explained in connection with Fig. 2.

The closure of the ground connection at the contacts 29 and 30 of the acting station will cause the circuit to be grounded when the contacts 21, 22 and 23 are closed after the first break of the signal; said contacts being so arranged that the connection between the two circuit contacts is established through the ground contact, thus making it impossible to close the circuit (while the contacts 29 and 30 are closed) without grounding it, although one side or the other of the circuit may be closed through the ground slightly before both sides are closed, in the event that, when the ground contact 23 is raised by the code-wheel, it touches one of the contacts 21 or 22 slightly prior to touching the other.

Upon closure and grounding of the signaling circuit, as just described, the relays B, C and D will be effectively energized, their armatures will move to attracted position, the local circuits controlled by relays B and D will be broken and the local circuit controlled by relay C will be closed. Upon the breaking of the local circuits of

relays B and D, as just described, registers E and G will each act to manifest one stroke of a signal, to set their respective paper feeding trains in motion, and to thereby break the contacts 41 and 42 associated with said trains; and the closing of the local circuit controlled by relay C will cause the register F to act in a similar manner.

During the remainder of the rotation of the code-wheel 20 of the acting station, the contacts 21, 22 and 23 will be alternately opened and closed in accordance with the intended code signal of such station, thereby causing alternate de-energization and re-energization of the magnets of relays B, C and D, so as to cause suitable response by the registers E and G. Inasmuch as the local circuit controlled by the relay C will be broken at the contacts 41 and 42 of register T and G throughout the action of such registers in response to such a signal, it is evident that the register F will not respond to any impulses, other than the first impulse, of any signal manifested by registers E and G.

Should some one or more of the initiating stations be short-circuited, and, while such short-circuit is effective, should a station so short-circuited be set in action, the register F will respond to the code signal of such station, but the registers E and G will not respond thereto. If, for example, the station M is short-circuited as suggested by the dotted line 60,—the circuit will not be broken when the first notch of the code-wheel is presented to the trailing end of the contact 23; but, before the contacts 21, 22 and 23 are closed by the left-hand wall of said first notch, the disc 34 will move the contact 30 into engagement with the contact 29, so that when said contacts 21, 22 and 23 are again closed, the circuit will be grounded and thereby cause the energization of relay C and response of register F. Inasmuch as the register F responds to closures but not breaks in the ground connection; it is evident that said register will respond to that closure of said ground connection which immediately precedes coming to rest of such a station; but will not cause such response when the disc 34 permits the contact 30 to move away from the contact 29, just before the mechanism of such station comes to rest, although the ground connection of said station will be interrupted, and the armature of relay C will move to retracted position and thereby break the local circuit including the controlling magnet of register F.

Inasmuch as the effectiveness of the energization of the magnets of relays B and D will be unimpaired by the breaking and closing of the contacts 21, 22 and 23 of station M while said station is subjected to the short-circuit 60, it is evident that

neither the register E or the register G will respond to such breaks or closures, and the local circuit controlled by the relay C will therefore continue to be responsive to said 5 relay throughout the code signal formulated by said contacts. After the last closure of the last round of the signal, the disc 34 will permit the contact 30 to move away from the contact 29 so that, when the mechanism 10 of such transmitting station comes to rest, the ground connection of such station will be ineffective. Upon the interruption of such ground connection, the relay C will be de-energized, and its armature 15 will move to retracted position, thereby breaking the local circuit controlled by said relay so as to de-energize the controlling magnet of register F. Inasmuch as said register acts only in response to the energization 20 of its controlling magnet, said register will not act in response to the interruption of the ground connection just described.

If an unintended ground develops upon 25 the circuit, as suggested by the dotted lines 61,—the relay C will be energized thereby closing the local circuit controlled by said relay so as to cause the register F to act, to light the alarm lamp 37 and to cause 30 the alarm bell 39 associated with said local circuit to sound continuously. If desired, said bell 39 may be silenced by means of the switch 40, pending the repair of the circuit to eliminate such ground connection. 35 While said ground connection remains effective, it is evident that register E will be in condition to act in response to circuit breaks at initiating station L and that register G will be in condition to act in response 40 to circuit breaks at initiating stations M or N, so that signals of these stations may be properly manifested by one or the other of said circuit registers while such an unintended ground remains effective. 45

If the signal circuit is broken as, for example, at some point along the conductor 46, relays B and D will be de-energized, registers E and G will act, and the lamps 37 associated with said registers will be lighted and the associated bells 39 will sound. If desired, said bells may be silenced, by means of the switches 40 associated therewith, pending the repair of the break in the circuit. While the circuit is thus broken, it is evident that should any initiating station be actuated the grounded closures of one side or the other of the circuit incident to the code signal thereof will be manifested by a corresponding one or the other of the circuit registers E and G; that the first impulse of such signal will be responded to by the register F, and that said register will not respond to the subsequent impulses of such signal because the

local circuit therefor will be broken at the contacts 41 and 42 of the acting circuit register E or G.

Should any two of said initiating stations be set in motion so as to act simultaneously in providing the first circuit break incident to the formulation of their respective code signaling impulses, it is evident that relays B and D will be de-energized when the circuit is thus broken; and, should the contacts of such stations subsequently act in unison to close and break the circuit path, both registers E and G will act in response to such closures. During such first break, the discs 34 of both of such stations will act 70 to close the contacts 29 and 30 thereat, so that, when the contacts 21, 22 and 23 of either (or both) of said stations next close, the relay C will be effectively energized and thereby cause the register F to act. While 80 the register F is thus acting, one or both of the registers E and G will also act to start their paper feeding train and thus close contacts 41 and 42 thereat, so that the register F will not act in response to any of the subsequent circuit closures incident to the concurrent action of such initiating stations. 90

Assuming that the stations L and N have been set in motion so as to simultaneously act in formulating the first circuit break incident to their respective code signals,—it is evident that said stations will act at or about the same time to close the circuit after said first break, and that the registers E, F and G will therefore respond to said closure 95 at or about the same time; but when the second notch of the code-wheel 20 of station N permits the contact 23 to move away from the contacts 21 and 22 thereat, it is evident that the corresponding contacts of station L will remain closed, the current path through relay D being thus interrupted while the current path through relay B will be held closed through the ground connection of station L. It is likewise evident that whenever the circuit is broken at station L while the code signaling contacts of station N are closed, the relay B will be de-energized but the effectiveness of the energization of relay 100 D will not be impaired, such effectiveness being maintained because of the current path established through the ground connection of station N. In view of the foregoing 105 it is evident that the code signal of station L will be fully and correctly manifested by the register E, and the code signal of station N will be correspondingly manifested by the register G; while the register F will manifest but one signaling impulse throughout said code signals. 110

Should two initiating stations operate concurrently, one starting somewhat in advance of the other, it is evident that the response of the registers would be similar to that just described, one of the registers re- 115 120 125 130

sponding to one of said stations, and the other of the resistors responding to the other of said stations. If one of such stations commences the transmission of its code signal during the series of the current impulses incident to the formulation of a round of the signal of the other of said stations,—the register acting, in response to the station thus starting during the round of the previously acting station, will manifest strokes of the signal broken into preceding its manifestation of the strokes of the first round of the signal which subsequently starts, but all following rounds or repetitions of such subsequently starting signal will be completely and correctly manifested by said register.

If more than two initiating stations act concurrently, the code signals of the currently acting stations nearest the respective ends of the circuit will be manifested as already described, the concurrent signal formulations of intervening stations being ineffective, because the circuit will be at all times either broken or grounded at both sides of such intervening stations.

Should the ground connection of any initiating station become ineffective, warning of that fact will be given whenever a code signal is received from such station, through the absence of response of the register F to the first closure of such code signal. Should the central office ground connection become ineffective, warning will be correspondingly given by the failure of the register F to act in response to any signals.

The use of a signaling system comprising electromotive forces differing in phase from one another and provided for the energization of various signal circuit current paths is not herein broadly claimed, as same forms the subject-matter of my co-pending application No. 335,430, filed November 3rd, 1919.

The foregoing description together with the accompanying drawing will suggest to those skilled in this art many other embodiments of this invention, and I therefore do not wish to be limited by the embodiment so described and shown; but what I claim and desire to secure by Letters Patent of the United States is:

1. In code signal manifesting mechanism for a circuit having alternative current paths,—means for responding to signaling impulses distinctively as to respective ones of two of such paths, and means operable incidentally to manifestations of impulses distinctive of one of said paths to prevent manifestations in response to impulses in the other of said paths.

2. In code signal manifesting mechanism for a circuit having alternative current paths,—a manifestor arranged for response to signaling impulses in a predetermined one only of said paths, and means respon-

sive to signaling impulses in another of said paths to be conditioned upon each such impulse to act for a predetermined interval thereafter to prevent responsive action of said manifestor.

3. In code signal manifesting mechanism for a circuit having alternative current paths,—a manifestor for signaling impulses in one of said paths, and means responsive to signaling impulses in another of said paths to be conditioned upon each such impulse to act for a time thereafter, longer than the longest interval between the impulses of any signal, to prevent responsive action of said manifestor.

4. In code signal manifesting mechanism for a circuit having alternative current paths,—a manifestor for signaling impulses in one of said paths, recording mechanism responsive to signaling impulses in another of said paths and comprising a paper feeding train adapted to be conditioned upon each such impulse to act for a time thereafter longer than the longest interval between the impulses of any signal, and means arranged to prevent responsive actuation of said manifestor during the running of said train.

5. In code signal manifesting mechanism for a circuit having alternative current paths,—a manifestor for response to signaling impulses in one of said paths, a recorder responsive to signaling impulses in another of said paths and having a paper feeding train adapted to be conditioned upon each signaling impulse to run for a predetermined interval, contacts so operable by said train as to be abnormally positioned during the running thereof, and electrical connections controlled by said contacts whereby said manifestor will be rendered unresponsive while said contacts are abnormally positioned.

6. In code signal manifesting mechanism for a circuit having alternative current paths,—a manifestor for response to signaling impulses in one of said paths, a recorder responsive to signaling impulses in another of said paths and having a paper feeding train adapted to be conditioned upon each signaling impulse to run for a time longer than the longest interval between the impulses of any signal, contacts so operable by said train as to be abnormally positioned during the running thereof, and electrical connections controlled by said contacts whereby said manifestor will be rendered unresponsive while said contacts are abnormally positioned.

7. In code signal manifesting mechanism for a circuit having alternative current paths,—means for responding to signaling impulses distinctively as to respective ones of three such paths, and means operable incidentally to manifestations of impulses

distinctive of either or both of two of said paths to prevent manifestations in response to impulses in the third of said paths.

8. In code signal manifesting mechanism for a circuit having alternative current paths,—a manifestor for response to signaling impulses in one of said paths, and means distinctively responsive to signaling impulses in two other of said paths to be conditioned upon each impulse in either or both of such paths to act for a time thereafter longer than the longest interval between the impulses of any signal to prevent response of said manifestor to impulses in said first named path.

9. In code signal manifesting mechanism for a circuit having alternative current paths,—a manifestor for signaling impulses in one of said paths, recorders respectively responsive to signaling impulses in other of said paths and each having a paper feeding train adapted to be conditioned upon each impulse of any signal responded to thereby to run for a time thereafter longer than the longest interval between the impulses of any signal, and means arranged to prevent responsive actuation of said manifestor during either separate or concurrent running of said trains.

10. In code signal manifesting mechanism for a circuit having alternative current paths,—a manifestor for signaling impulses in one of said paths, recorders respectively responsive to signaling impulses in other of said paths and each having a paper feeding train adapted to be conditioned upon each circuit impulse to run for a predetermined interval and contacts so operable by said train as to be abnormally positioned during the running of said train, and electrical connections controlled by said contacts whereby said manifestor will be rendered unresponsive while any of said contacts are abnormally positioned.

11. In code signal manifesting mechanism for a circuit connecting current supply

mechanism arranged to jointly supply said circuit and a ground connection,—a manifestor for response to signaling impulses in said ground connection, recorders responsive to signaling impulses in respective sides of said circuit and each having a paper feeding train adapted to be conditioned upon each signaling impulse to run for a time longer than the longest interval between the impulses of any signal, contacts so operable by said trains as to be abnormally positioned during the running of said trains, respectively, and electrical connections controlled by said contacts whereby said manifestor will be rendered unresponsive while any of said contacts are abnormally positioned.

12. A circuit connecting current supply mechanism arranged to jointly supply such circuit and a ground connection, in combination with code signal manifesting mechanism comprising means for distinctively manifesting signaling impulses in respective sides of said circuit and signaling impulses in said connection, and means operable incidentally to manifestations of signaling impulses in either or both sides of said circuit to prevent manifestations in response to impulses in said connection.

13. A circuit connecting current supply mechanism arranged to apply relatively out-of-phase electromotive forces to the respective sides of said circuit and to a ground connection, in combination with code signal manifesting mechanism comprising means for distinctively manifesting signaling impulses in respective sides of said circuit and signaling impulses in said connection, and means operable incidentally to manifestations of signaling impulses in either or both sides of said circuit to prevent manifestations in response to impulses in said connection.

In witness whereof, I hereunto subscribe my name, this 5th day of January, 1920.

CLARENCE E. BEACH.
